US0D1025076S

(12) **United States Design Patent** (10) **Patent No.:** **US D1,025,076 S**
(45) **Date of Patent:** **** Apr. 30, 2024**

(54) **DOCKING STATION**

(71) Applicant: **Shenzhen Donghao Times Technology Co., Ltd**, Guangdong (CN)

(72) Inventor: **Heng Zhang**, Guangdong (CN)

(73) Assignee: **Shenzhen Donghao Times Technology Co., Ltd**, Shenzhen (CN)

(**) Term: **15 Years**

(21) Appl. No.: **29/916,562**

(22) Filed: **Nov. 14, 2023**

(51) LOC (14) Cl. **14-02**

(52) U.S. Cl.

USPC **D14/434**; D14/433

(57) **CLAIM**

The ornamental design for a docking station, as shown and described.

DESCRIPTION

FIG. 1 is a front, left, and top perspective view of a docking station, showing my new design;

FIG. 2 is a rear, right, and bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is a front, left, and top perspective view of a second embodiment of the docking station, showing my new design;

FIG. 10 is a rear, right, and bottom perspective view thereof;

FIG. 11 is a front elevation view thereof;

FIG. 12 is a rear view thereof;

FIG. 13 is a left side elevation view thereof;

FIG. 14 is a right side elevation view thereof;

FIG. 15 is a top plan view thereof;

FIG. 16 is a bottom plan view thereof;

FIG. 17 is a front, left, and top perspective view of a third embodiment of the docking station, showing my new design;

FIG. 18 is a rear, right, and bottom perspective view thereof;

FIG. 19 is a front elevation view thereof;

FIG. 20 is a rear view thereof;

FIG. 21 is a left side elevation view thereof;

FIG. 22 is a right side elevation view thereof;

FIG. 23 is a top plan view thereof; and,

FIG. 24 is a bottom plan view thereof.

The unshaded surfaces shown between the solid lines and the broken lines form no part of the claimed design.

The broken lines in the drawings depict portions of the docking station that form no part of the claimed design.

1 Claim, 24 Drawing Sheets
